[57] CLAIM

The ornamental design for a finned heat exchanger for electronic equipment, as shown and described.

DESCRIPTION

FIG. 1 is a front view of a finned heat exchanger for electronic equipment, showing our new design;
FIG. 2 is a plan view thereof;
FIG. 3 is a right side view thereof;
FIG. 4 is a left side view thereof;
FIG. 5 is a rear view thereof;
FIG. 6 is a bottom view thereof; and
FIG. 7 is a front perspective view thereof.

FIG. 2

FIG. 1

FIG. 3

FIG. 6

FIG. 4

FIG. 5

FIG. 7
